GOLF BALL PUTTING GAMES

Filed Sept. 11, 1947

FIG. 1.

FIG. 2.

FIG. 3.

Inventor
JOSEPH ANTHONY
By *W. H. S. Mark*
Attorney

UNITED STATES PATENT OFFICE

2,497,390

GOLF BALL PUTTING GAME

Joseph Anthony, Hamilton, Ontario, Canada

Application September 11, 1947, Serial No. 773,465

2 Claims. (Cl. 273—32)

1

My invention relates to improvements in golf ball putting games, and the object of the invention is to provide a game wherein the player puts a golf ball along a channel; the open end of the channel, towards which the ball rolls, terminating in the vicinity of a mechanically driven oscillating hazard member which is interposed between the open end of the channel and an area having golf ball receiving holes therein.

A further and particular object of my invention is to furnish a game of skill wherein the objective of the player is to so time the putting of the ball, that the ball reaches the oscillating hazard member at such a moment in the member's movement when it is possible to obtain the highest score, and another object of the invention is to provide a construction wherein the ball having entered one of the holes returns down an inclined surface for replay.

With the foregoing and other objects in view as shall hereinafter appear, my invention consists of a golf ball putting game constructed and arranged all as hereinafter more particularly described and illustrated in the accompanying drawing in which:

Fig. 1 is a plan view of one construction of my game.

Fig. 2 is a vertical longitudinal cross-sectional view taken through the line 2—2, Fig. 1.

Fig. 3 is a similar view to Fig. 1 showing an alternative construction, and

Fig. 4 is an enlarged fragmentary vertical cross-sectional view taken through the line 4—4, Fig. 3.

Like characters of reference indicate corresponding parts in the different views of the drawing.

My game as illustrated in Figs. 1 and 2 consists of a putting area 2 from where the player puts a ball along an open ended channel 3. The end 4 of the game platform opposite the putting area is of substantially semi-circular shape and the ball travels around to the open end 5 of the channel.

The end 5 of the channel opens into an area 6 having a plurality of ball receiving holes 7 therein, into one of which holes the ball may drop. The area 6 is sloped downwardly towards the putting area, so that the ball rolls towards the player. A sloping deck 8 is positioned underneath the area 6 and on which the ball drops upon entering any of the holes 7. The lower end of the deck has an inclined wall 9 extending thereacross to guide the downwardly rolling ball on the deck 8 towards the left hand corner of

2

the game, whereby the ball can be picked up for re-play.

The area 6 has a trough 10 formed therein which extends from the curved end to the putting area and terminates with a ball receiving hole 11. A mechanically driven oscillating hazard member is positioned at the entrance to the trough 10 and consists of a vertically oscillatable arm 12 formed with an upturned end plate 13 extending through an orifice 14 in the area 6 at the entrance to the trough 10. A vertically positioned disc 15 is rotated by a geared electric motor 16 and is furnished with a crank pin which extends through a slot 17 in the arm 12. The end of the arm 12 opposite to the plate 13 is pivoted upon a suitably mounted pin 18, so that as the disc rotates the arm 12 swings upwardly and downwardly whereby its plate 13 moves between the lowermost position shown in dotted lines to the uppermost position shown in full lines. It will thus be appreciated that the oscillations of the plate 13 will cover and uncover the entrance to the trough 10.

The holes 7 and hole 11 have various scoring points, the hole 11 giving the highest score. The player's objective is to so time the putting of the ball that the ball will pass from the end of the channel 3 towards the end of the trough 10 at the moment that the plate 13 is in the lowermost position, whereby the ball may enter the trough 10 and roll downwardly to enter the hole 11. If the player miscalculates the timing, the ball will strike the plate 13 and thus be prevented from entering the trough 10 and will roll downwardly over the central portion of the area 6 and possibly drop into one or other of the holes 7. When the ball, having entered a hole 7, comes to rest after rolling down the deck 8, it will lie underneath the hole 11 which is of such a size that the ball can be lifted therefrom for re-play.

In Figs. 3 and 4 I show an alternative form of the invention wherein the ball receiving channel 19 extending from the putting area 2 is of wide mouth form and curves around at its end 20 to direct the ball into a horizontal oscillating hazard member. This member consists of a pair of upper and lower discs 21 and 22 retained in spaced relationship by a pair of converging walls 23 which form with the upper and lower discs 21 and 22 a funnel 24 into which the ball enters.

The lower disc 22 is mounted upon a centrally positioned spindle 25 journaled within a bearing plate 26 and carrying a crank arm 27. The crank arm 27 is connected to a crank 28 upon an electric motor 29 by a connecting rod 30; the

drive being so dimensioned that as the crank 28 rotates the crank arm 27 oscillates with the resultant oscillation of the funnel 24.

The lower disc 22 of the funnel assembly is substantially flush with the upper face of a deck 31 which contains a plurality of ball receiving holes 32 positioned at the ends of troughs 33 which radiate from the periphery of the disc 22 and have their ball entrance ends within the compass of the swinging movement of the narrow end of the funnel 24.

An indicating arrow 34 is carried upon the top face of the disc 21 so that the player may gauge the oscillations of the funnel when putting the ball.

The holes 32 have various scoring points and the objective of the game is to putt the ball at such a time that it will be directed cleanly through the funnel and enter the channel 33 of the hole earning the highest score. For example with the funnel in the position as shown in Fig. 3 the ball will roll therethrough and enter the central channel whereas if the ball enters the funnel 33 as the funnel is approaching either end of its stroke, the ball will strike against one or the other of the walls 23 and will probably be delivered into one of the lower scoring holes. The construction shown in Fig. 3 is formed with a lower sloping deck, similar to the construction shown in Fig. 1 and upon which the ball will drop upon entering one of the holes 32 and roll downwardly towards the putting area where it can be retrieved through a suitably positioned orifice. It will be readily apparent that my game may be so constructed that the ball upon entering any of the holes will close an electrical contact whereby a vertical illuminated score board will indicate the score in the same manner as in electrically illuminated pin ball games.

Although I have shown and described a particular embodiment of my invention it is to be understood that I may make such changes and

alterations as I may from time to time deem necessary without departing from the spirit of my invention as set forth in the appended claims.

What I claim as my invention is:

- 5 1. A golf ball putting game of the character described comprising an area from which the player puts the ball, an open ended channel extending from the area and along which the ball rolls after it has been struck, a deck formed 10 with a plurality of troughs in its face which terminate with ball receiving holes, and a power driven oscillatable hazard member of funnel shape which continually oscillates while the player puts and having its large orifice directed towards the 15 end of the channel and its small orifice directed towards the ends of the trough, said troughs being arranged between the limits of oscillation of the small end of the funnel, the small end of the funnel being only large enough to direct the ball into one trough.
2. A golf ball putting game as claimed in claim 1, wherein the funnel shaped hazard member is oscillatable in a horizontal plane about a pivot point disposed substantially centrally of the funnel, the troughs being radially disposed in relation to the pivot point.

JOSEPH ANTHONY.
